Attorney.

UNITED STATES PATENT OFFICE.

CARL G. THOMPSON, OF KNOXVILLE, TENNESSEE.

FILLED-SACK-SEWING MACHINE.

1,403,922.

Specification of Letters Patent. Patented Jan. 17, 1922.

Application filed August 6, 1920. Serial No. 401,609.

To all whom it may concern:

Be it known that I, CARL G. THOMPSON, a citizen of the United States, residing at Knoxville, in the county of Knox and State 5 of Tennessee, have invented certain new and useful Improvements in Filled-Sack-Sewing Machines, of which the following is a specification.

This invention relates to means for sewing 10 up the open ends of sacks which have previously been filled with any desired material; and it consists in the novel construction and combination of the parts hereinafter fully described and claimed whereby sacks of different heights are sewed up with facility and 15 are subsequently graded or sorted according to their height.

In the drawings, Figure 1 is a front view 20 of a filled sack sewing machine constructed according to this invention. Fig. 2 is an end view of the same, taken in section on the line 2—2 in Fig. 1. Fig. 3 is a sectional plan view of portions of the machine taken on the line 3—3 in Fig. 1. Fig. 4 is a plan view 25 of the discharging arms and one end portion of the conveyer.

A stationary support 7 for the entire machine is provided, and this support is generally the floor and floor joists of the building 30 in which the machine is placed. A conveyer for supporting the filled sacks is provided, and it may be a flat topped endless conveyer of any approved construction, but in carrying out this invention the conveyer preferably 35 consists of two similar endless conveyer aprons or belts 8 arranged side by side at an obtuse angle to each other, so that their upper stretches form a channel for receiving and supporting the bottoms of the sacks. 40 When a flat topped conveyer is provided much time is lost in flattening the bottoms of the filled sacks so that the sacks will stand upright on the conveyer without falling over. The sacks are filled in any approved 45 way, and they will stand upright in the channel formed by the two stretches without any special preparation.

An open space or channel is formed between the lower and adjacent edges of the top 50 stretches of the two belts 8, and the middle parts of the bottoms of the sacks are free to bulge into this space as shown in Fig. 2.

The two aprons or belts 8 are driven simultaneously in the same direction and at the 55 same speed by any suitable driving mechanism. Similar rollers 9 are provided at each

end of the aprons, and the rollers at one end are provided with beveled toothed wheels 10 on the lower end portions of their shafts 12. These wheels are driven by means of beveled 60 toothed wheels 14 secured on a countershaft 15, and the countershaft has a worm wheel 16 secured on it. A worm 17 is provided for driving the worm wheel, and is secured on a main driving shaft 18. The above men- 65 tioned shafts are journaled in any suitable stationary bearings, and the main driving shaft 18 is revolved by any approved engine or motor. Stationary brackets 23 having inclined top portions 22 are provided for sup- 70 porting the intermediate portions of the upper stretches of the conveyer aprons.

A crosshead 24 is provided, and has a vertical upright 25 for supporting the sewing mechanism secured to one end portion of 75 it, and arranged to slide in a guide 26 secured to the support or floor 7. The crosshead is arranged in the room or chamber below the floor 7, and a platform 27 for the operator is secured by an upright 27, to its other end 80 portion. This platform is secured to a slide 28 which slides vertically in a guide 29 secured to the support or floor 7. The slide and guide are preferably square in cross-section, but they may be cylindrical, or of 85 any other shape which will work satisfactorily.

A frame 30 is secured to the floor 7, and 31 are guide sheaves carried by this frame. Counterbalance weights 81 for the crosshead 90 and the parts connected to it are provided, and are secured to the ends of cords 32 which pass over the sheaves 31, and have their other ends secured to the crosshead. The crosshead is raised and lowered by 95 means of any approved mechanism or device for that purpose, and in the form of the invention shown a screw 34 is provided. This screw engages with a screwthreaded hole 35 at the middle part of the crosshead 24. The 100 upper end portion 36 of the screw revolves in a bearing 37 on the frame 30, and its lower end portion revolves in a stationary step 38. A beveled friction wheel 40 is secured on the screw at a little distance above the step. 105

A countershaft 42 is arranged to slide longitudinally in stationary bearings 43, and is provided with a pulley 44 for driving it from the main driving shaft 18, by a belt 45. Two beveled friction wheels 46 are se- 110 cured on the countershaft 42, and are ar- ranged one on each side of the friction wheel

40. The screw is revolved to raise and lower the crosshead by placing the wheels 46 in engagement alternately with the wheel 40, and the shaft 42 is slid longitudinally by the 5 operator by means of a lever 47 and intermediate connections. The operator stands on the platform 27, and 48 is a back rest for him to lean against. The lever 47 is pivoted to the crosshead by a pin 50, and it has 10 a longitudinal slot 51 in its lower end portion. The upper end or handle portion 49 of the lever extends through the guide 29, and works in a slot in the platform.

A bracket 52 is provided and is slidably 15 connected at one end to the lower end portion of the lever 47 and its slot, and its other end 53 is arranged to engage with the circumferential groove 54 of a collar 55 secured on the countershaft 42. Any other 20 approved form of operating device may be provided however for starting and stopping the devices for lifting and lowering the crosshead.

The sewing mechanism 60 is secured to the 25 upper and curved end portion 61 of the upright 25, and is of any approved sort suitable for sewing up the tops of the sacks. This sewing mechanism can advantageously 30 be driven by an electric motor 62 carried by the upright 25.

The sacks are of various heights, and when filled they are placed on the conveyer, and are moved by it under the sewing mechanism to the position indicated by the dotted lines 63. The angular shape of the channel positions the sacks relatively to the sewing mechanism. The conveyer is not stopped while the crosshead is operated to adjust the sewing mechanism to the height of the 40 sack. The crosshead adjusts the platform, which supports the operator, simultaneously with the sewing mechanism, so that the operator is always in the same relative position with respect to the sewing mechanism, 45 and is able to work it to the best advantage.

When the top of the sack has been sewed up and closed, the conveyer carries the sack from under the sewing mechanism and discharges it. Stationary vertical standards 65 are provided, and are arranged at different distances from the sewing mechanism at the sides of the conveyer. These uprights have horizontal arms 66 secured to them at different levels above the conveyer, and these 55 arms project diagonally across the upper stretches of the conveyer in the path of the sacks. The arms are adjustable vertically on the standards, and are secured by set-screws 67 or other fastening devices. As 60 many standards are provided as will sort the sacks into the desired number of grades. The highest sacks strike the arm of the first standard which is arranged the highest above the conveyer, and are tilted over and 65 thrown off the conveyer. Shorter sacks are

conveyed farther by the conveyer, and are thrown off it by arms arranged at a suitable distance above it for them to engage with. The shortest sacks are discharged at the extreme end of the conveyer.

70

What I claim is:

1. In a filled sack sewing machine, a support for the sacks, a crosshead arranged below the sack support, a vertical upright and a platform for the operator carried by the 75 said crosshead, sewing mechanism carried by the said upright and arranged above the sack support, and lifting mechanism for raising and lowering the crosshead and thereby simultaneously adjusting the position of the platform and the sewing mechanism relative to the sack support. 80

2. In a filled sack sewing machine, a support for the sacks, a crosshead extending crosswise under the sack support, a vertical 85 upright and a platform for the operator carried by the opposite end portions of the crosshead and arranged one on each side of the sack support, sewing mechanism carried by the said upright and arranged above the 90 sack support, and lifting mechanism for adjusting the position of the crosshead vertically relative to the sack support.

3. In a filled sack sewing machine, a stationary support, a support for the sacks arranged above the stationary support, a crosshead arranged below the stationary support, a vertical upright and a platform for the operator carried by the said crosshead, guides for the said upright and platform carried by the stationary support, sewing mechanism carried by the said upright and arranged above the sack support, and lifting mechanism for adjusting the position of the crosshead vertically relative to 105 the sack support.

4. In a filled sack sewing machine, a support for the sacks, a crosshead extending crosswise under the sack support, a vertical upright and a platform for the operator carried by the opposite end portions of the crosshead and arranged one on each side of the sack support, sewing mechanism carried by the said upright and arranged above the 110 sack support, a screw engaging with the middle part of the crosshead, and means for revolving the said screw so as to adjust the position of the crosshead vertically relative to the sack support. 115

5. In a filled sack sewing machine, a support for the sacks, a crosshead arranged below the said support, a vertical upright and a platform for the operator carried by the said crosshead, sewing mechanism carried by the said upright and arranged above the 125 sack support, a screw engaging with the crosshead, driving mechanism for revolving the screw, and means for reversing the direction of motion of the screw, said means being supported by the crosshead and pro- 130

vided with an end portion which projects above the said platform.

6. In a filled sack sewing machine, a sewing mechanism, an endless traveling conveyer which supports the sacks under the sewing mechanism and permits them to be tilted over laterally, and a stationary discharging arm arranged diagonally over the conveyer in the path of the upper portions 10 of the sacks and adapted to tilt the sacks laterally off the conveyer at one side thereof as the sacks are pressed into contact with it by the conveyer.

7. In a filled sack sewing machine, a sewing mechanism, an endless traveling conveyer which supports the sacks under the sewing mechanism and permits them to be 15

tilted over laterally, and stationary discharging arms arranged diagonally over the conveyer at different levels and adapted to 20 tilt the sacks laterally off the conveyer at different points of its length according to the height of the sacks.

8. In a filled sack sewing machine, a sewing mechanism, an endless traveling conveyer which supports the sacks under the sewing mechanism, stationary standards arranged adjacent to the conveyer, and discharging arms secured to the standards at 25 different levels and projecting diagonally 30 across its upper stretch.

In testimony whereof I have affixed my signature.

CARL G. THOMPSON.
